PANY, INC., A CORPORATION OF NEW JERSEY.

MUFFLE FURNACE.

Application filed July 12, 1926. Serial No. 121,792.

This invention relates particularly to an electric muffle furnace for use in making artificial teeth. In the baking of artificial teeth certain basic conditions are recognized as essential for the production of a uniform product. First, relatively high temperature (1300-1400° C.) must be maintained over the whole mass of material being baked; second, a neutral or slightly oxidizing atmosphere must exist within the chamber enclosing the teeth being baked to avoid variation in color shading, and third, the material while baking must be protected from foreign material which would at the baking temperature adhere to the surface of the teeth and ruin the product.

The majority of teeth today are baked in oil-fired furnaces which are exceedingly inefficient and objectionable on account of the high room temperature maintained and its effect upon operators, and the difficulty of maintaining an oxidizing atmosphere within the muffle and the prevalence of floating dust which spoils the surface of the teeth. Attempts have been made also to bake teeth with gas-fired furnaces but these are open to the same general objection as oil-fired furnaces, and it is also more difficult to maintain a neutral or oxidizing atmosphere within the baking oven. Many attempts have been made to substitute for these furnaces electric furnaces of the resistor type, but to meet the baking conditions it is necessary that the electric resistor first should have a melting temperature materially above that to which the teeth are to be subjected, and second, should be of a non-oxidizing character. This first requirement eliminates all of the cheaper metals of the non-oxidizing character. The other base metals having the necessary high melting point unfortunately oxidize at a very low temperature. We have found that platinum is the best metal to use as the electrical resistor for furnaces for this particular work, and as this metal is of high intrinsic value it is necessary to so design a furnace that a minimum amount of this precious metal will be required. This means that the electric resistor should be placed as close as possible to the material that is to be baked and so positioned with reference to the external walls of the furnace, that the loss of heat outwardly by radiation and con-

duction is reduced to a minimum. It is further necessary that the support for the electric resistor (in this case the muffle) should have a high electrical resistance at the working temperatures to avoid short circuiting of the resistor; it should not react chemically with the resistor nor should it contain material which softens or flows at the maximum temperature of baking. Very pure alumina has been found best to meet these several conditions, and muffles made of this material, with as thin wall as possible and of an internal area as small as feasible to bring the source of the heat as close as possible to the product being baked, are wound with the electric resistor through which the necessary current is passed to attain the desired temperature.

One object of the invention is to provide a muffle furnace embodying novel and improved features of construction whereby the furnace can be easily and quickly assembled and disassembled with a minimum possibility of injury to the electric heating resistor when repairs are necessary.

Another object is to provide a muffle furnace which includes a novel and improved construction and combination of a muffle and a casing or housing therefor, the housing consisting of a plurality of easily separable parts and enclosing the muffle without imposing its weight thereon with an air gap heat insulation between the housing and the muffle on all sides except the bottom, said parts being so related that the muffle can be quickly removed by disassembling the housing.

Other objects are to provide a muffle furnace of the character described wherein the muffle is so shaped and positioned as to insure maximum concentration of developed heat upon the material with minimum loss of heat by radiation and conduction to the external walls of the furnace; to provide a simple, inexpensive, and durable muffle furnace, and to obtain other results and advantages as may be brought out by the following description.

Referring to the accompanying drawings, in which corresponding and like parts are designated throughout the several views by the same reference characters,

Figure 1 is a vertical longitudinal sectional

view through an electric muffle furnace embodying the invention, and

Figure 2 is a front elevation partially in section with the closure plug for the muffle removed.

Specifically describing the illustrated embodiment of the invention, the reference character A designates the base of the furnace which may consist of a plurality of fire brick 1, said base being substantially rectangular in plan and having mounted thereon a vertical metal casing 2 open at its top as at 3.

Arranged upon the base A is a sub-base 4 which is preferably in the form of a flat tile having an upstanding flange or rib 5 around three sides thereof. On the top of the sub-base 4 is a layer of powdered heat and electricity insulating material 6 which may be magnesia, and resting upon said layer of insulating material is a thin slab or plate 7 which may be of the same material as the sub-base 4. This plate 7 forms a seat or support for a muffle 8 which is substantially elliptical in cross-section with its bottom side slightly flat to firmly rest upon the plate 7, said muffle preferably being of the same material as the sub-base 4. Helically wrapped around the muffle in the usual manner is a ribbon 9 of electricity conducting material, for instance platinum, which serves as an electric heating coil, the extremities of the ribbon being returned upon themselves as indicated at 10 and having secured thereto by suitable clamps 11 electric wires or cords 12 by which the coil is connected to the circuit.

A cover 13 which is preferably of the same material as the sub-base 4 is mounted upon said sub-base within the perimetral flange 5 on the sub-base and in spaced relation to the muffle, the shape of the cover substantially corresponding to that of the muffle but sufficiently larger to allow an air gap of one-half inch or more between the top and side walls of the muffle and corresponding interior walls of the cover. It will be observed that this construction provides the best heat insulation on the sides and top of the muffle, namely a sealed volume of air, and also that the roof of the muffle is relieved of the weight of the heavy heat insulating material above its cover and only bears the burden of its own roof and a part of the encircling resistor. This construction materially prolongs the life of the muffle. The cover comprises a top 130, sides 131 and a closed end 132. The bottom of the cover which rests upon the sub-base is open so that the cover may be slipped over the muffle, and the end of the cover corresponding to the open end of the muffle is also open. The top of the cover is provided with slots 14 through which the extremities of the ribbon 9 may be passed outwardly from the muffle.

The side of the casing 2 corresponding to the open end of the cover 13 and muffle 8 is provided with an opening 15 within which is arranged a face block or tile 16 which has an opening 17 in substantial axial alignment with the opening in the muffle 8. A filling tile or block 18 is interposed between the face tile 16 and the end of the muffle and sub-base 4, the top and sides of the filling tile being spaced inwardly from the top and sides of the face tile a distance substantially equal to the thickness of the cover 13, as indicated at 19. It will be noted that the open end of the muffle 8 and the corresponding end of the sub-base 4 are in juxtaposed relation, and the filling tile abuts said ends of the muffle and the sub-base to form an end wall for the casing. The filling tile also has an opening 20 in substantial alignment with the opening 17 and the opening in the muffle. A closure plug 21 is provided for closing the opening 17, and preferably the said opening and said plug are tapered to make a wedge fit. When the furnace is in operation, the joints 22, 23 between the cover 13 and the face block 16 and filling block 18 are cemented; and the joint 24 between the end of the muffle 8 and the filling block is also cemented. The filling block 18 is also secured to the face block 16 as by cement.

Vent openings 28 are provided in the muffle for free circulation of air, and a thermocouple 29 may be inserted into the muffle through a hole 31 in the muffle and opening 30 in the cover.

In assembling the furnace, the muffle is placed upon the plate 7 through the open top of the casing 2, whereupon the joint 24 is cemented. The cover 13 is then placed upon the sub-base 4 and the extremities 10 of the ribbon 9 drawn outwardly through the slots 14. The joints 22 and 23 are then cemented. The wires 12 are then connected to the extremities 10 of the ribbon by the clamps 11, and the closure plug 21 is fitted into the opening 17. Granular heat and electricity insulating material 25 is then poured into the casing 2 around the cover 13, after which the electric current may be turned on and the furnace heated to the desired temperature as indicated by the thermocouple projecting into the back of the muffle, whereupon the plug 21 is removed and the tray carrying the teeth to be baked is inserted into the muffle and the plug 21 replaced. In disassembling the furnace for repairs, the reverse operation of assembling takes place, the granular material 25 being first permitted to flow outwardly by action of gravity through discharge openings 26 in the casing 2. These openings are normally closed by suitable gates such as sliding plates 27. The clamps 11 are then disconnected from the ends 10 of the ribbon, and

the joints 22 and 23 broken and the cover 13 removed, after which the joint 24 is broken and the muffle removed.

With this construction, it will be observed that the muffle can be easily and quickly placed in and removed from the furnace by simple disassembling of the housing or casing which consists of the base 4, cover 13, filling block 18 and face block 16. The joints between the cover 13 and the sub-base 4 filling block and face block are so arranged as to retard the escape of heat from the muffle and to prevent the sifting of the insulating material 25 into the muffle; and furthermore, the particular construction of the casing is simple and inexpensive.

While we have shown and described the invention as embodied in certain details of construction, it will be understood that this is primarily for the purpose of illustrating the principles of the invention and that many modifications and changes may be made in said details by those skilled in the art without departing from the spirit or scope of the invention. Therefore, we do not desire to be understood as limiting ourselves except as required by the following claims when construed in the light of the prior art.

Having thus described the invention, what we claim is:

1. In a muffle furnace, the combination of a casing to receive a muffle and having an opening at its top to receive granular heat insulating material and an opening in one side, a muffle housing including a base having an end wall formed with a charging opening accessible through said side opening of the casing, a closure for said charging opening, and a muffle cover having an open bottom with its edges removably resting upon said base and one end open the edges of which separably abut said end wall of said base, a muffle removably mounted upon said base and having one open end the edges of which abut said end wall of said base around said charging opening, the top, sides and other end of said muffle being in spaced relation to said cover to form a

closed air heat insulating space between the muffle and said cover, an electric heating coil surrounding said muffle, and granular heat insulating material in said casing surrounding said muffle housing, said muffle housing protecting said muffle against the weight of said granular insulating material.

2. A muffle furnace comprising a base, a face block having an opening, a filling block secured to one side of said face block with its top and sides spaced inwardly of the top and sides of said face block, said filling block having an opening in alinement with said opening in the face block, a muffle removably mounted on said base with its open end abutting said filling block and in alinement with said opening in the filling block, an electric heating coil surrounding said muffle, and a cover for the muffle having an open bottom with its edges removably resting upon said base and one open end the edges of which separably overlie the top and sides of said filling block and separably abut said face block, whereby said muffle is wholly enclosed.

3. A muffle furnace comprising a base having an end wall formed with an opening and an upstanding flange extending around the other end and sides thereof, a closure for said opening, a muffle removably mounted on said base inwardly of said flange with its open end in abutting relation to said end wall and in substantial alinement with said opening in said end wall, a cover for said muffle having an open bottom with its edges removably resting upon said base and fitting in contacting relation within said upstanding flange, said cover having one open end the edges of which are adapted to separably abut said end wall of the base, the top, sides and other end of said cover being in spaced relation to said muffle whereby said muffle may be wholly enclosed within a closed air heat insulating space, and an electric heating coil surrounding said muffle in contact therewith.
